TELEVISION ANTENNA SELECTOR KNOB

Marvin P. Middlemark, Rego Park, N. Y.

Application May 21, 1956, Serial No. 41,582

Term of patent 7 years

(Cl. D26—13)

Figure 1 is a front perspective view of a television antenna selector knob showing my new design;

Figure 2 is a side elevational view thereof; and

Figure 3 is a cross-sectional view through the knob.

The broken line showing of a television antenna structure is for illustrative purposes only. The dominant features of my design reside in those portions shown in full lines.

I claim:

The ornamental design for a television antenna selector knob, substantially as shown and described.
